UNITED STATES PATENT OFFICE.

ISAAC P. TURNER, OF TROY, NEW YORK, ASSIGNOR TO MARSHALL & BRIGGS, OF SAME PLACE.

CUFF.

SPECIFICATION forming part of Letters Patent No. 252,341, dated January 17, 1882.

Application filed November 9, 1881. (No model.)

To all whom it may concern:

Be it known that I, ISAAC P. TURNER, of the city of Troy, county of Rensselaer, and State of New York, have invented a new and useful Improvement in Apparel-Cuffs; of which the following is a specification.

My invention consists, as hereinafter to be described, of the relative form given to and the manner employed to unite the blanks from which apparel-cuffs are made, and in which one of the blanks is cut from the fabric so as to have a width which is double that of the other blanks used, and when folded longitudinally near its center, and an intermediate thickness of linen having half the width of the double blank is placed between the folds of the latter, and the side edges of both blanks are stitched and the united blanks turned through either of their unsewed ends, the double blank will form with one of its folds the exterior facing of the cuff and with its other fold a thickness of the intermediate ply, with the linen blank inserted between its folds before being stitched and turned, forming the linen exterior of the cuff, when the parts are reversed by turning. The additional blank used to form with one fold of the double blank the intermediate stiffening-ply is sewed before the parts are turned, at the same time that the other parts are stitched, and is then placed next to and what is the outside of that one of the double-blank folds which, when the parts are sewed and turned to reverse their relative position, forms the exterior of the cuff-facing.

The object of my invention is to produce from a continuous piece of fabric a blank which can be folded longitudinally, so that one of its folds will form the whole facing of the cuff and the other fold a thickness of the intermediate ply, and so that the line of its longitudinal fold may be varied to shorten up more or less the width of the fold forming the ply, and thus meet the varying measures of shrinkage occurring in the material used, and so avoid the necessity of employing differing blank-patterns to produce the same kind of cuff with uniformity.

In the accompanying drawings, forming a part of this specification, there are eight figures illustrating my invention, and in all of

which the same letter-reference as to the designation of parts is used.

Figure 1 shows the double blank, the line of its longitudinal fold being indicated by a dotted line, which is shown as placed a little below its center. Fig. 2 illustrates the linen blank which is placed between the folds of the double blank, and which with one fold of the double blank forms the exterior faces of the cuff when stitched and turned. Fig. 3 designates the blank which forms with one fold of the double blank the intermediate ply. Fig. 4 indicates the position of the blanks when placed together to be stitched, with parts of them cut away at one corner and a line of stitching produced upon one of their sides to connect them. Fig. 5 shows a vertical section taken on the line *x x* of Fig. 4, with the thickness of the blanks enlarged to better show them, and the section also made longer for the same purpose. Fig. 6 illustrates a section of the blanks enlarged unequally to illustrate their position when the longer ones are curled outwardly so as to bring the edge of the narrower blank to coincide with the other edges, after one side has been stitched, to stitch the others. Fig. 7 shows a completed cuff; and Fig. 8, a section taken through Fig. 7, with the parts unequally enlarged to better illustrate them, and taken on the line *e e*.

The several parts are designated by letter-reference, and the manner of putting them together to form a cuff thus described.

The letter B indicates a blank of about double the vertical width of the blanks C and D, and the vertical widths of the two latter are equal. The blank B is folded horizontally on the line *d d*, and this gives to the fold *A'* a greater vertical width than that of the fold *A*.

Between the folds of the blank B is placed the blank C, and upon the outer surface of the fold *A'* is placed the blank D, with the lower edges of all the blanks so placed parallel. While in this position the row of stitching *s' s'* is run to connect them together. The blanks, thus sewed upon their edges at one side, are then stitched upon the other side by bending outwardly the wider blanks, so as to make the edges of the latter and that of the shorter fold *A* coincide with the parts in the position in-

dicated in Fig. 6, the line of stitching which so secures them being indicated at s'' s'' . The 5
ply fold A^2 is thus narrower than the others, which is an advantage when the cuff is turned, and its relative difference in vertical width when compared with the others may be varied upon folding it to suit the differing shrinkages of material, and thus the use of one blank-pattern may take the place of several as they are generally 10
used. After the blanks are thus folded, applied to each other, and stitched together at their side edges, as has been described, they are turned through either of their unsewed ends. The latter are then turned in and the usual 15
row of border stitching is run around the ends and sides in continuity, which secures the ends. When the cuff is thus finished the fold A' forms the facing of the cuff, the blank C its linen exterior, and the narrower fold A^2 a part of the 20
intermediate ply when more than one thickness of the latter is used, and the whole of the 25
ply when a three-ply cuff is made, for my invention in its entirety can be applied to produce a three or four or five-ply cuff, and to any form of cuff in which a double blank can be used, in substantially the same manner.

Having thus described my invention, what I claim, and desire to secure by Letters Patent, is—

30 1. In an apparel-cuff, the combination of the double blank B , made of a continuous piece of fabric adapted to be folded longitudinally so

as to produce the unequal folds A' and A^2 , and the linen blank C , placed between the folds of the double blank when folded down for stitching their side edges, to form with the blank C and the wider fold A' the exterior of the cuff, and with the narrower fold A^2 the intermediate ply, or a thickness of the ply, when the parts are placed with reference to each other, 35
stitched at their side edges and turned through either of their unsewed ends, in the manner herein shown and described.

2. An apparel-cuff made with the double blank B folded longitudinally to produce the 40
unequal folds A' and A^2 , the linen blank C placed between the said folds of the double blank when laid, the blank D placed next to the fold A' , with the parts sewed together near the edges of their sides, their side edges coinciding, and then turned through either of their unsewed ends, so that the blank C will form the linen exterior of the cuff, the fold A' its facing, the blank D and the fold A^2 its intermediate ply, with the ends of the cuff turned in 45
and the whole border stitched, as herein shown and described.

Signed at Troy, New York, this 7th day of November, A. D. 1881.

ISAAC P. TURNER.
